CLAIM

The ornamental design for a charging controller grips as shown and described.

DESCRIPTION

FIG. 1 is a top perspective view of a charging controller grips showing our new design;

FIG. 2 is another top perspective view thereof;

FIG. 3 is a front view thereof;

FIG. 4 is a rear view thereof;

FIG. 5 is a left view thereof;

FIG. 6 is a right view thereof;

FIG. 7 is a bottom view thereof;

FIG. 8 is a top view thereof;

FIG. 9 is an enlarged view of an encircled portion of the charging controller grips labeled 9 in FIG. 2;

FIG. 10 is an enlarged view of an encircled portion of the charging controller grips labeled 10 in FIG. 4; and,

FIG. 11 is an enlarged view of an encircled portion of the charging controller grips labeled 11 in FIG. 7.

The long-dash short-dash broken lines shown in the drawings depict enlargement boundaries that form no part of the claimed design. The evenly-dashed broken lines shown in the drawings illustrate portions of the charging controller grips that form no part of the claimed design.

1 Claim, 11 Drawing Sheets
